United States Patent Office.

JOHN T. WEBSTER, OF NEW YORK, ASSIGNOR TO DEBORAH POWERS, ALBERT E. POWERS, AND NATHANIEL B. POWERS, OF LANSINGBURG, NEW YORK.

Design No. 3,467, dated April 27, 1869.

DESIGN FOR A FLOOR-CLOTH.

The Schedule referred to in these Letters Patent and making part of the same.

To all whom it may concern:

Be it known that I, JOHN T. WEBSTER, of the city, county, and State of New York, have invented or produced a new and original Design for Floor Oil-Cloths, or other fabrics; and I do hereby declare that the same is fully shown upon the drawings, which accompany this specification, which are hereby declared to be part of the same; and

What I claim as my invention, and desire to secure by Letters Patent of the United States, is—

The design for floor oil-cloths, or other fabrics, as shown upon the aforesaid drawings.

JOHN T. WEBSTER.
